(57) **CLAIM**

We claim the ornamental design for a cover for a measurement sensor, as shown and described.

DESCRIPTION

FIG. 1.1 is a top perspective view of a cover for a measurement sensor embodying our design;

FIG. 1.2 is a bottom perspective of FIG. 1.1;

FIG. 1.3 is a top plan view of FIG. 1.1;

FIG. 1.4 is a bottom view of FIG. 1.1;

FIG. 1.5 is a left vertical elevational view of FIG. 1.1;

FIG. 1.6 is a right vertical elevational view of FIG. 1.1;

FIG. 1.7 is an end vertical elevational view of FIG. 1.1; and,

FIG. 1.8 is an opposite end vertical elevational view of FIG. 1.1.
